UNITED STATES PATENT OFFICE.

MILLARD SUMTER BLACK, OF HUNTINGTON PARK, CALIFORNIA.

CASING PERFORATOR.

Application filed January 9, 1925. Serial No. 1,441.

This invention relates to a casing perforator and has particular reference to that type of perforator intended to operate on pipe or casing in a well, or the like.

5 An object of this invention is to provide a perforator of the character referred to in which there are two parts operating on the casing at substantially the same point.

10 Another object of my invention is to provide a perforator of the character referred to in which the cutting means is particularly simple and inexpensive of manufacture.

15 It is a further object of my invention to provide a simple, effective perforator which will effectively perforate two casings of different sizes, one arranged within the other.

20 Another object of my invention is to provide a perforator including two cutting parts mounted independently and arranged to operate so that one operates to feed the other into operation.

25 The various objects and features of this invention will be apparent to those familiar with the art upon consideration of the following detailed description of a typical form of the invention throughout which description reference is had to the accompanying drawings in which

30 Fig. 1 is a front elevation of the perforator embodying the present invention.

35 Fig. 2 is a detailed sectional view of the main portion of the perforator showing it arranged within the innermost of two casings, one arranged within the other, and in a partially actuated position.

40 Fig. 3 is a view similar to Fig. 2 showing the parts completely actuated.

45 Fig. 4 is a transverse sectional view taken as indicated by line 4—4 on Fig. 3 and

50 Fig. 5 is a transverse sectional view taken as indicated by line 5—5 on Fig. 3.

55 The perforator provided by this invention is useful generally for perforating casing or pipe in a well, or the like. Because of the ability of the perforator to cut or punch outwardly a comparatively great distance, it is particularly useful in situations where it is desired to perforate two strings of casing or pipe of different size, one arranged within the other or where the pipe or casing is surrounded by a body of cement, or the like, and it is desired to perforate not only the casing, but also the body of cement. I will throughout this disclosure refer to the device as applied to or as operating on two casings A and B of different sizes, one arranged within

the other, the casing A being the innermost casing, the casing B being the outermost casing. It is to be understood, however, that this particular situation is merely one in 60 which the perforator may be advantageously used, and that the broader aspects of the invention are therefore not to be considered limited by such specific disclosure.

65 The perforator provided by this invention comprises, generally, a body 10, two cutters 11 and 12 mounted in or carried by the body and means 13 to actuate one of the cutters.

70 The body 10 constitutes a frame or carrier for the other parts of the tool and is preferably substantially round in cross-sectional configuration and of a size to freely operate in the casing A. The body is sufficiently long to properly carry the other parts and to have 75 the necessary characteristics. The body 10 as shown in the drawings is provided at its upper end with a tapered screw threaded projection or pin 14 by which the tool may be connected with a suitable operating member 80 or means such, for instance, as a string of drill pipe or operating line. The two punches or cutters 11 and 12 are mounted in a recess 15 provided in the body 10. The recess is disposed longitudinally of the body 85 and extends inwardly from one side of the body to a point close to the other side thereof. In practice the recess may be milled or otherwise formed in a body 10 which is solid, or a 90 recess may be formed by constructing the body in sections which assemble to form the recess.

95 Of the two cutters 11 and 12 the cutter 11 is the principal or main cutter while the cutter 12 is, or at least may be, what I will term a pilot cutter, operating to start operation and to feed or start actuation of the main cutter 11. The main cutter 11 is mounted in the recess 15 so that it is operable between a position where it is entirely within the confines 100 of the body and a position where it projects a substantial distance from the body, the two positions just mentioned being illustrated in Figs. 2 and 3 of the drawings respectively. In accordance with the preferred form of the invention the main cutter 11 is pivotally mounted in the recess at the or in the upper end thereof. In the drawings I have illustrated the main cutter 11 mounted at the upper end of the recess 15 on a pivot pin 18 and 110 have shown the inner end of the cutter rounded or curved concentric with the pin 18

and seated in the rounded upper inner corner of the recess 15. The cutter 11 is provided with an enlargement 11^a in the form of a hub. The upper end of the recess is enlarged at 5 11^b to receive the hub so that the hub operates to receive part of the strain coming on the cutter. By mounting the main cutter in the upper end part of the recess the upper end wall 22 of the recess 15 operates to form a 10 stop for the cutter, in its extended or completely actuated position as illustrated in Fig. 3. It is to be noted from inspection of the drawings that main cutter 11 is comparatively long, being sufficiently long to penetrate both the casing A and the casing B when 15 in the extended position as illustrated in Fig. 3.

The pilot cutter 12 is mounted in the recess 15 below the main cutter 11. The pilot cutter 20 is preferably pivotally mounted in the bottom or inner part of the recess, for instance, by means of a pivot pin 30 and is preferably shaped and proportioned so that it will engage and operate on only the inner 25 casing A. The pilot cutter is operable between and in position such as is indicated by dotted lines in Fig. 2 where it is completely within the confines of the body 10 and an actuated position where it has moved to or 30 past a position in which it has operated on the inner casing A. The pilot cutter is mounted and proportioned so that it engages the inner casing A at an angle to readily operate on it when actuated as hereinafter described. 35 When I refer to the pilot cutter as "operating on" the casing A, I do not mean that the pilot cutter shall necessarily penetrate or perforate the casing A, for in accordance with the broader aspects of my invention the pilot cutter may only dent or grip the casing A in a manner sufficient to accomplish the operation hereinafter described. In accordance with my present invention the 40 pilot cutter 12 is related to or spaced below the main cutter 11 so that the pilot cutter upon or after operating on the casing A engages and operates the main cutter to start the main cutter moving outwardly and so that the main cutter upon moving outwardly 45 engages the casing A at substantially the same point, if not at exactly the same point, operated on by the pilot cutter. In other words, the pilot cutter is related to the main cutter so that it operates on the casing A and 50 starts the main cutter in operation on the casing A so that the main cutter is started in operation in a manner to continue so that it perforates the casing A and also the casing B. As shown in the drawings the pivotal axis of 55 the pilot cutter is spaced below the pivotal axis of the main cutter a distance less than the combined lengths of the cutters causing the pilot cutter to engage and operate the main cutter. The spacing of the pivotal axes 60 65 and the lengths of the cutters may be related

so that the points or cutting parts of the cutters are together or adjacent at a point outside the body during operation of the tool. In a case where the pilot cutter is made to fracture or dent the casing A the main cutter 70 operates to follow up and increase the operation on the casing A to the extent of cutting a substantial hole in the casing A. In the preferred form of the invention the lower portion of the recess carrying the pilot cutter 75 is wider than the upper part, so that the body has shoulders 35 which operate to limit upward movement of the pilot cutter so that the pilot cutter is always in position ready to return to its in position as illustrated in 80 dotted lines in Fig. 1.

In accordance with the broader aspects of my invention any suitable means may be provided for starting operation of the pilot cutter to cause it to operate on the casing A in 85 the manner just described. In the form of the invention illustrated in the drawings the operating means comprises a wedge 36 slidably mounted in the recess 15 below the pilot cutter, a tail piece, or other suitable device, arranged below the lower end of the body 10 to grip or form anchorage in the casing A, and a rod 41 connecting the tail piece 40 and wedge 36. When the device is unactuated the wedge is in engagement with the 90 lower end wall 42 of the recess 15 and the pilot cutter is supported or stopped in its in position by the wedge as clearly illustrated by dotted lines in Fig. 2. The wedge is designed and proportioned so that when it is 95 moved upwardly in the recess 15 it operates to throw the pilot cutter outwardly until it has engaged and started operation of the casing A. The parts may be proportioned so that the wedge is stopped in its upward movement 100 as soon as the pilot cutter has started operation of the casing A as it is unnecessary to completely actuate the pilot cutter by means of the wedge. The upward movement of the wedge may be stopped by proportioning the 105 rod 41 so that the upper end of the tail piece 40 engages the lower end of the body 10 when the wedge has been actuated as far as is desired. It is to be understood, of course, that the tail piece 40 may be of any design or construction, such element being no part of the 110 present invention except as it enters into the general combination of elements.

From the foregoing description it is believed that the operation of the device will be 115 clearly and fully understood. The usual method of operation is as follows. The device is lowered into the inner casing A at the lower end of a drill pipe or operating line to the desired point in the casing. The tail piece 120 is tripped or actuated to grip or resist movement in the casing A. With the parts in position where the cutters 11 and 12 are in their 125 positions the body 10 is moved downwardly. This causes the wedge to move the pilot cutter 130

12 out into position where it operates on the casing A as hereinabove described. During operation of the pilot cutter on the casing A or immediately thereafter, the pilot cutter 5 engages the outer end portion of the main cutter causing the main cutter to start movement outwardly so that it engages the casing A, at, or very close to the point operated on by the pilot cutter. The casing having been 10 operated on and the main cutter being fed by the pilot cutter the main cutter penetrates the casing A to perforate it, if the pilot cutter has not already done so, or to enlarge or continue the perforation already made by the 15 pilot cutter. Continued downward movement of the body 10 will cause the main cutter to continue in its outward movement so that it engages and perforates the outer casing B and finally is stopped in its completely extended position as illustrated in Fig. 3.

Having described only a typical preferred form of my invention I do not wish to limit myself to the specific details hereinabove set forth, but wish to reserve to myself any 25 changes or variations that may appear to those skilled in the art or fall within the scope of the following claims.

Having described my invention, I claim:

1. A device of the character described including a body, two individually mounted cutters carried by the body, and means whereby one cutter is operated by the other.

2. A device of the character described including, in combination, a body, two cutters carried by the body having pivotal axes spaced apart a distance less than the combined lengths of the cutters with one cutter adapted to engage and actuate the other, and cutter actuating means.

3. A device of the character described including, in combination, a body, two cutters of different lengths carried by the body and having pivotal axes spaced apart a distance less than the combined lengths of the cutters 45 one cutter operating the other, and cutter actuating means.

4. A device of the character described including, in combination, a body, two cutters of different lengths carried by the body and having pivotal axes spaced apart a distance less than the combined lengths of the cutters, the cutters having cooperating parts whereby the shorter cutter operates the longer cutter, and cutter actuating means.

5. A device of the character described including, in combination, an elongate body, two cutters pivotally carried by the body with their pivotal axes spaced apart longitudinally of the body a distance less than the combined lengths of the cutters whereby one cutter cooperatively engages the other, and cutter actuating means.

6. A device of the character described including, in combination, an elongate body, 65 two cutters of different lengths pivotally car-

ried by the body, the pivotal axes of the cutters being spaced apart longitudinally of the body a distance less than the combined lengths of the cutters whereby one cutter cooperatively engages the other, and cutter actuating means. 70

7. A tool to be operated in a casing including, in combination, a body to extend into the casing, two cutters carried by the body on pivotal axes spaced apart a distance less than the combined lengths of the cutters and related so that the cutters operate to engage the casing at the same point, and cutter actuating means. 75

8. A tool to be operated in a casing including, in combination, a body, two cutters of different lengths carried by the body on pivotal axes spaced apart a distance less than the combined lengths of the cutters so that the shorter cutter operates the longer cutter, the 80 cutters having active parts that are adjacent outside the body during the operation of the tool to penetrate a single part of the casing, and cutter actuating means. 85

9. A tool to be operated in a casing including, in combination, a body, two cutters of different lengths carried by the body on pivotal axes spaced apart a distance less than the combined lengths of the cutters, and means for actuating the short cutter so that 90 it operates on the casing, the cutters being related so that the long cutter is fed into engagement with the casing by the short cutter. 95

10. A tool to be operated in a casing including, in combination, a body, two cutters of different lengths carried by the body and having individual pivotal mountings, the axes of which are spaced apart a distance less than the combined lengths of the cutters, the short cutter being adapted to operate on the casing 100 when actuated and the cutters being related so that the long cutter is moved into engagement with the casing by the short cutter to continue operation on the casing started by the short cutter, and cutter actuating means. 105

11. A tool to be operated in a casing including, in combination, a body, two cutters of different lengths carried by the body and having pivotal mountings spaced apart a distance less than the combined lengths of the cutters so that the shorter cutter operates on the casing when actuated and engages the outer portion of the long cutter to feed it into operative engagement with the casing, and means for actuating the short cutter. 115

12. A tool to be operated in a casing including, in combination, a body, two cutters normally within the body, the cutters being of different lengths and being pivotally mounted on axes spaced apart a distance less than the combined lengths of the cutters, the cutters being related so that the short cutter operates on the casing when actuated and feeds the long cutter into engagement with the casing, the long cutter being operable to a 125 130

position where it projects a substantial distance from the body, and means for stopping the long cutter in said actuated position.

13. A device of the character described including, in combination, a body, two cutters of different lengths and having pivotal axes spaced apart a distance less than the combined lengths of the cutters so that one cutter oper-

ates the other, means for stopping operation of the long cutter in position where it projects a substantial distance from the body, and cutter actuating means. 10

In witness that I claim the foregoing I have hereunto subscribed my name this 29th day of December, 1924.

M. SUMTER BLACK.
